UNITED STATES PATENT OFFICE.

MELVIN FELLOWS, OF CHENEY, WASHINGTON, ASSIGNOR OF ONE-FOURTH TO GEORGE A. FELLOWS, ONE-FOURTH TO JOHN H. WINTER, AND ONE-FOURTH TO JOHN M. BENIDICT, ALL OF CHENEY, WASHINGTON.

FIRE-EXTINGUISHER.

1,217,428.

Specification of Letters Patent. Patented Feb. 27, 1917.

Application filed January 20, 1915. Serial No. 3,340.

To all whom it may concern:

Be it known that I, MELVIN FELLOWS, a citizen of the United States, residing at Cheney, in the county of Spokane and 5 State of Washington, have invented certain new and useful Improvements in Fire-Extinguishers, of which the following is a specification.

The object of this invention is to equip 10 grain treating machines with means for preventing dust fire and dust explosion such as frequently results during operation thereby not only causing a loss of time but serious loss of property and life.

15 Spontaneous combustion sometimes results from the constant and intense vibration to which the dust particles are subjected, the resulting heat often rendering the particles incandescent. This friction 20 set up is not only due to engagement of the dust particles with structural parts, but also to friction generated by the particles moving rapidly through the air. Sometimes static charges are generated, due to this excessive friction, and in such cases disastrous 25 results from fire and explosion often occur. Now during operation of a machine of this character, such for instance as a threshing machine, the attention of the operatives is 30 so concentrated upon the work being performed that incipient developments of explosion and fire are not noticed until it is too late to bring to bear any kind of efficient remedy for preventing disastrous 35 results.

It is one of the objects of this invention to equip a grain treating machine such as a threshing machine, fanning mill, and like machines of this character, with means for 40 constantly, although not necessarily continuously, treating the interior dust laden atmosphere in such a manner as to prevent such causes of fire and explosion from even developing in its incipiency, much less actually starting, thereby rendering machines of this character absolutely safe.

A further novel feature consists in equipping machines of this character with apparatus for extinguishing a fire after the 45 same has been started.

In the drawings:

Figure 1 is a view in side elevation of a threshing machine showing applied thereto one form of the device of my invention.

Fig. 2 is a sectional view on line 2—2 55 of Fig. 1.

Fig. 3 is a sectional view on line 3—3 of Fig. 2.

Fig. 4 is an enlarged elevation of that portion of the apparatus. 60

Fig. 5 is a sectional view on line 5—5 of Fig. 4.

Fig. 6 is an enlarged view partly in elevation and partly in section showing an improved valve mechanism. 65

Like characters of reference designate similar parts throughout the different figures of the drawings.

As illustrated, 1 designates as a whole, a threshing machine provided with a housing 70 2 for the internal mechanism thereof, certain of the side boards of the housing being omitted for purposes of illustration. A blower 3 is shown connected with the discharge end of the housing 2 and a stacker 75 4, communicates with the blower 3. The threshing machine is shown to be of the portable type, bearing wheels being indicated at 5 and 6.

During the passage of the grain from the threshing cylinder 7 throughout the several sieves 8 to the blower 3, the entire interior space in the housing 2 is thickly permeated with dust resulting from the threshing operation. Notwithstanding the action of the 80 blower 3, the dust is generated so rapidly that all of the air inside of the housing 2 is heavily laden with dust, and the latter is in a continuous state of the most intense agitation. It will be readily seen how susceptible to ignition this dust is, when it is considered that it is not only in a thoroughly dry state but is subjected to a fairly high temperature in the housing by reason of the hot atmosphere under which the machine is operated. When to these conditions is added the fact that a great deal of friction is generated by the agitation of these dust particles, their susceptibility to ignition will be readily appreciated. 95 100

It will also be clear that if the atmosphere in the interior of the housing is substantially continuously treated with a view of neutralizing and also positively rendering such dust laden atmosphere non-combustible, that the causes hitherto prevalent will be rendered harmless.

In the specific form shown, I run a plurality of spray pipes 9, preferably longitudinally of the housing 2, all of said pipes being suitably connected with a manifold 10, the spray pipes being suitably perforated for the discharge therefrom in efficient distribution of a suitable preventive or extinguishing medium. A supply pipe 11 is connected with the manifold 10, and interposed in the supply pipe 11 is an intermittently operating valve 12, which may be of the rotating type. The valve 12 is provided with a valve stem 13 on which a worm wheel 14 is mounted. A worm 15, suitably journaled, meshes with worm wheel 14 and is mounted upon a worm spindle 16. Spindle 16 is provided with a keyed sleeve 17, slidably thereon, and provided with pin locking slots 18. A driving spindle 19 telescopes sleeve 17 and is provided with pins 20 for engagement with the pin slots 18 to prevent relative independent rotation of spindles 16 and 19 when the parts are in the adjustment shown in Fig. 6. A bevel gear 21 is mounted on spindle 19 and meshes with a bevel gear 22 on shaft 23. Shaft 23 may be any one of the constantly operated shafts of the threshing machine. The supply pipe 11 is also interrupted by an emergency valve which comprises a valve casing 24 and a valve closure 25. The latter is of the rotating type and is ported at 26, so that it may be brought into and out of registry with supply pipe 11. The intermittent or service valve 12 may be internally constructed in a manner similar to the emergency valve just described.

Supply pipe 11 leads to a tank 27 which is shown provided with a hand hole 28 and a suitable closure 29 therefor. Said tank 27 is also provided with a removable head 30 to permit of ingress and egress for charging and cleaning operations, respectively. The tank 27 will be charged by a suitable chemical such for instance as sodium carbonate, and within the tank 27 is a frangible container 31, in which is disposed a chemical such as sulfuric acid.

The container 31 may be in the form of a glass bottle, and I provide a holder therefor which comprises a spring clip 32 having a yielding lining 33. The spring clip 32 may be provided with a clasp device comprising members 34 and 35. The spring clip 33 is mounted upon a base 36 from which supporting rods 37 and 38 depend

from the interior of the tank 27 to support the bottle 31 in the manner shown in Fig. 2. 65

Within the tank 27 is disposed an agitating device which may comprise a rod 39 extending through a suitable stuffing box 40, in one end of the tank. Attached to the rod 39, in suitable spaced relation, is a 70 plurality of agitators 41, for agitating the tank contained ingredient of the extinguishing medium. To one of said agitators 41 is attached a breaking device which may be in the form of a rod 42. Said rod 42 75 is disposed in such a manner that during initial reciprocation of the rod 39 to the left of Fig. 2, it will engage and break the container 31 so that the contents of the latter will combine with the tank ingredient 80 to produce carbon dioxid. An operating lever 43 is pivoted to the removable head 30, at 44, and is provided with an operating end 45. The operating lever 43 is slotted at 46 and a pin 47 on rod 39 projects 85 through said slot 46 to form an operative connection between rod 39 and lever 43. Lever 43 is connected by a link 48 with arm 49 of emergency valve 24.

After rod 39 has been reciprocated so as 90 to obtain a considerable generation of the extinguishing medium, then the lever 43 will be allowed to rest so that port 26 will register with supply pipe 11. This will permit the extinguishing medium flowing 95 through the spray pipes and into the interior of the housing 2 to extinguish a fire that has been started from any of the causes hereinbefore enumerated.

A hose cock 50 may constitute connecting 100 means in case it is desired to use a hose for extinguishing an external blaze. Should it be desired to increase the internal pressure in tank 27, I may provide means such as an air pump 51, connected with the tank 105 by means of a pipe 52. A pressure gage 53 is also provided.

Now the primary function of the foregoing mechanism, just described, is to act as an emergency extinguisher in case of fire 110 having actually started.

I will now describe the novel construction whereby the same source of supply may be utilized as a service fire preventing apparatus.

115 Service containers 54 adapted to contain sulfuric acid or any one ingredient to be combined with the more bulky tank ingredient employed, are disposed partly in the tank 27. Packing glands 55 preserve an 120 air tight fit and the containers are mounted on supports 56. The upper ends of the containers 54 are closed by stoppers 57 and the lower ends are closed by stoppers 58. Stoppers 58 are held in partly open positions 125 to permit the contents to slowly drip out of

containers 54, by means which may comprise angle arms 59, connected with the stoppers 58, and extending through packing glands 60. The arms 59 are suitably threaded so 5 as to be engaged by adjusting nuts 61.

Now during normal operation, the parts will be so connected that the emergency valve 24 will be normally open. There will be a constant but limited generation of carbon dioxide in the tank 27 because of the 10 dripping discharge from containers 54. The service valve 12 will intermittently open the supply to the spray pipes 9 so that the interior atmosphere of the housing 2 will be 15 intermittently sprayed with any suitable medium that may be selected. Under any ordinary circumstances, no fire can start because the same would be quenched in its incipiency, or more accurately speaking, the 20 primal causes would be prevented from acting to such an extent as to actually develop combustion. However, in case that generation was not sufficient, or if for any other reason a fire should actually start, the emergency means incorporated in the mechanism 25 just described could be brought into action to supplement or rather take the place of the service means.

It will be seen that I have embodied in a 30 single mechanism, combined constant service and emergency features which render the device of my invention capable of effectually meeting any exigency that could possibly arise, of the character referred to.

35 I claim:—

1. In combination, a machine provided 40 with a housing and means for intermittently treating the air in said housing during operation of said machine, substantially as described.

2. In combination, a machine provided 45 with a housing, a source of supply of fire preventing or extinguishing medium, and a constantly operated valve means opening and closing for causing an intermittent discharge of such medium onto said housing, substantially as described.

3. In combination, a machine comprising 50 a housing, a tank carried by said housing for the generating a supply of fire extinguishing medium, a supply pipe leading from said tank, spray pipes leading from said supply pipe and extending interiorly of said housing, an emergency valve in said 55 supply pipe, a service valve in said supply pipe, means for connecting said service valve with an operating portion of said ma-

chine to constantly operate said service valve, and agitator means operatively connected with said emergency valve for effecting an emergency generation of said medium, substantially as described.

4. In combination, a machine comprising 60 a housing, a tank carried by said housing for the generation of a supply of fire extinguishing medium, a supply pipe leading from said tank, spray pipes leading from said supply pipe, means for causing a constant but limited generation of said medium in said tank, and a constantly opening and closing valve in said supply pipe for controlling discharge of said medium from said spray pipes, substantially as described.

5. In combination, a machine comprising 65 a housing, a tank carried by said housing for the generation of a supply of fire extinguishing medium, a supply pipe leading from said tank, spray pipes leading from said supply pipe and extending interiorly of said housing, an emergency valve in said supply pipe, a service valve in said supply pipe remote from said emergency valve with respect to said tank, means connecting said service valve with a portion of said machine to constantly operate said valve, means 70 for causing a constant but limited generation of said medium in said tank, and agitator means operatively connected with said emergency valve for causing an emergency generation of such medium in said tank, substantially as described.

6. In a fire extinguishing mechanism for 75 a machine of the class described, a tank for containing one of the chemical ingredients to be combined, a frangible container in said tank holding the remaining chemical ingredient, an agitator extending through a packing box and into said tank and comprising a rod provided with a plurality of vanes for agitating the contents of said tank and one of said vanes having a device for disrupting said container on initial movement of said agitator, an operating lever for said agitator disposed outside of said tank, a pipe leading from said tank, and an emergency valve in said pipe operatively connected with said lever, substantially as 80 described.

In testimony whereof I affix my signature in presence of two witnesses.

MELVIN FELLOWS.
